(57) **CLAIM**

The ornamental design for a cover cap for medical aids, as shown and described.

DESCRIPTION

FIG. 1 is a perspective top view of a first embodiment of a cover cap for medical aids.

FIG. 2 is a side view of the first embodiment of the cover cap for medical aids.

FIG. 3 is a top view of the first embodiment of the cover cap for medical aids.

FIG. 4 is a bottom view of the first embodiment of the cover cap for medical aids.

FIG. 5 is a perspective bottom view of the first embodiment of the cover cap for medical aids.

FIG. 6 is a perspective top view of a second embodiment of a cover cap for medical aids.

FIG. 7 is a side view of the second embodiment of the cover cap for medical aids.

FIG. 8 is a front view of the second embodiment of the cover cap for medical aids.

FIG. 9 is a top view of the second embodiment of the cover cap for medical aids.

FIG. 10 is a bottom view of the second embodiment of the cover cap for medical aids; and,

FIG. 11 is a perspective bottom view of the second embodiment of the cover cap for medical aids.

In the drawings, the broken lines depict environmental subject matter only that forms no part of the claim.

The design relates to a cover cap for medical aids, the medical aids having cover caps which cover certain parts for speaking valves or artificial noses.
